US00D958278S

(12) **United States Design Patent** (10) **Patent No.:** **US D958,278 S**
(45) **Date of Patent:** **** Jul. 19, 2022**

(54) **TWO WHEELED BOARD**

(71) Applicant: **RAZOR USA LLC**, Cerritos, CA (US)

(72) Inventor: **Ian Desberg**, Cerritos, CA (US)

(73) Assignee: **Razor USA LLC**, Cerritos, CA (US)

(**) Term: **15 Years**

(21) Appl. No.: **29/754,633**

(22) Filed: **Oct. 13, 2020**

Related U.S. Application Data

(60) Continuation of application No. 29/710,760, filed on Oct. 25, 2019, now Pat. No. Des. 899,540, which is a continuation of application No. 29/674,375, filed on Dec. 20, 2018, now Pat. No. Des. 865,095, which is a continuation of application No. 29/627,176, filed on Nov. 22, 2017, now Pat. No. Des. 837,322, which is a division of application No. 29/571,692, filed on Jul. 20, 2016, now Pat. No. Des. 803,963.

(57) **CLAIM**

The ornamental design for a two wheeled board, as shown and described.

DESCRIPTION

FIG. 1 is a front, top, left-side perspective view of the two wheeled board of my design.

FIG. 2 is a rear, bottom, left-side perspective view of the embodiment of FIG. 1;

FIG. 3 is a top view of the embodiment of FIG. 1;

FIG. 4 is a bottom view of the embodiment of FIG. 1;

FIG. 5 is a front view of the embodiment of FIG. 1;

FIG. 6 is a rear view of the embodiment of FIG. 1;

FIG. 7 is a left-side view of the embodiment of FIG. 1; and,

FIG. 8 is a right-side view of the embodiment of FIG. 1.

The broken lines illustrate portions of the two wheeled board that form no part of the claim.

1 Claim, 7 Drawing Sheets
